US0D1104252S

(12) **United States Design Patent** (10) Patent No.: **US D1,104,252 S**
(45) Date of Patent: ** Dec. 2, 2025

(54) **ORAL IRRIGATOR**

(71) Applicant: **Fly Cat Electrical Co., Ltd.**, Shenzhen (CN)

(72) Inventor: **Xiao Liu**, Shenzhen (CN)

(73) Assignee: **Fly Cat Electrical Co., Ltd.**, Shenzhen (CN)

(**) Term: **15 Years**

(21) Appl. No.: **29/965,686**

(22) Filed: **Sep. 27, 2024**

(51) LOC (15) Cl. **28-03**

(52) U.S. Cl.

USPC **D24/111**

(58) **Field of Classification Search**

(57) **CLAIM**

The ornamental design for an oral irrigator, as shown and described.

DESCRIPTION

FIG. 1 is a front, right and top perspective view of an oral irrigator showing my new design;

FIG. 2 is a rear, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

The broken lines in the figures illustrate portions of the oral irrigator that form no part of the claimed design.

1 Claim, 8 Drawing Sheets
